UNITED STATES PATENT OFFICE.

MILROY G. STACKHOUSE, OF TULSA, OKLAHOMA, ASSIGNOR TO THE STASET COMPANY,
A CORPORATION OF DELAWARE.

NUT LOCK.

Application filed January 4, 1921. Serial No. 434,891.

To all whom it may concern:

Be it known that MILROY G. STACKHOUSE, a citizen of the United States of America, residing at Tulsa, in the county of Tulsa and State of Oklahoma, has invented new and useful Improvements in Nut Locks, of which the following is a specification.

The object of the invention is to provide a simple, inexpensive and efficient means for locking a nut in its set or adjusted position upon the bolt to which it is fitted, under such conditions as to prevent the displacement or removal of the nut except by mutilating or destroying the same; and furthermore to provide a device for the purpose indicated which can be operated in the locking of the nut with the minimum of effort and loss of time upon the part of the operator, and moreover to provide a locking means which can be applied to the nut when manufactured with the minimum of modification in the construction of the nut, and hence without materially adding to the cost thereof; and with these objects in view 25 the invention consists in a construction and combination of parts of which a preferred embodiment is shown in the accompanying drawings, wherein:—

Figure 1 is a view of a nut provided with a locking device embodying the invention as seen before the locking operation is effected.

Figure 2 is a similar view showing the lock in the engaged position.

Figure 3 is an inverted plan view of a nut provided with locking elements embodying the invention, one of the elements being shown in its normal or retracted position and the other in its locking or engaged position.

Figure 4 is a vertical sectional view taken in the plane of the locking elements.

Figure 5 is a section on the line 5—5 of Figure 4.

The locking device, of which any desired number may be used in connection with a nut such as that indicated at 10, consists of a hard metal web or blade 11 fitted in a radial kerf 12 formed in the under or inner surface of the nut, the walls of the kerf being disposed in overlapping relation with the bottom edges of the blade, being pinched together to frictionally hold the same in position with the inner end of the blade

adjacent to the bolt opening 12 and with the outer end thereof projecting beyond the angle or corner of the nut so as to be accessible by means of a hammer or like driving tool serving to impart a longitudinal movement radially of the nut to the blade or web to cause the impingement of the inner end thereof upon the threads of the bolt shown at 14, or the embedding of the said inner end in the threads of the bolt to lock the nut against rotary movement.

In practice the nuts may be placed on the market in the form indicated in Figure 1 with the outer ends of the blades or webs projecting, so that the nuts may be applied to the bolts in the ordinary way and screwed to an adjustment suiting the object in connection with which the bolt is used, whereupon a blow of the hammer directed against the outer end of the blade or web will cause the inner end thereof to engage the threads of the bolt to secure an efficient locking of the parts. The blade or web as above indicated should be of a metal such as steel which is sufficiently harder than the metal of the bolt to adapt it to cut or impress the latter and thus lock the nut against displacement either through jarring or vibration or by applying force in an effort to reverse or unscrew the nut, so that the removal of the nut may be effected only by a mutilation thereof.

Being disposed as they are in bi-secting relation with the corners of the nut with their driving ends protruding beyond said corners, the operation of seating the blades also results, when the blades are driven home, in peening over the edges of the nut at the corner and thus closing the slots at the end, thereby maintaining the blades in locked relation with the screw.

Having described the invention what is claimed as new and useful is:—

1. As an article of manufacture, a nut having in its inner surface a radial kerf extending into communication with the bolt opening, and a blade fitted in said kerf with its outer end projecting beyond the periphery of the nut for impact by a driving tool, the length of the blade exceeding the length of the kerf by an amount equal to the distance of penetration of the blade into the bolt to which the nut is attached.

2. As an article of manufacture, a nut

having in its inner surface a radial kerf bisecting an angle thereof and extending into communication with the bolt opening, and a blade fitted in said kerf with its outer end

5 projecting beyond the angle of the nut for impact by a driving tool, the length of the blade exceeding the length of the kerf by

an amount equal to the distance of penetration of the blade into the bolt to which the nut is attached.

10

In testimony whereof he affixes his signature.

MILROY G. STACKHOUSE.
